UNITED STATES PATENT OFFICE.

NATHANIEL B. RICE, OF CHICAGO, ILLINOIS, ASSIGNOR TO CHRISTIAN WAHL, OF SAME PLACE.

APPARATUS FOR CONDENSING OR DRYING LIQUIDS.

SPECIFICATION forming part of Letters Patent No. 292,950, dated February 5, 1884.

Application filed July 26, 1883. (No model.)

To all whom it may concern:

Be it known that I, NATHANIEL B. RICE, residing at Chicago, in the county of Cook and State of Illinois, and a citizen of the United States, have invented certain new and useful Improvements in Apparatus for Condensing or Drying Liquids, &c., of which the following is a full description, reference being had to the accompanying drawings, in which—

10 Figure 1 is a longitudinal vertical section on line y y of Fig. 2; Fig. 2, a cross-section on line x x of Fig. 1, and Fig. 3 a transverse vertical section on line z z of Fig. 1.

15 The object of this invention is to improve the construction and operation of apparatus to be used for evaporating liquids or liquid solutions, either with or without a vacuum; and its nature consists in bringing the channel to be traversed by the liquids or liquid solution into 20 a close compact form; in heating the apparatus by placing the heating-pipes over or out of contact with the liquids or liquid solution to be reduced or dried, and in the several parts and combinations of parts hereinafter described, 25 and claimed as new.

In the drawings, A indicates the main or central portion of the exterior casing; B B', the end sections; C, the section or passage for exhausting air; D, the exhaust-passage; E, inlet 30 for the liquid to be treated; F, outlet for the treated liquid; G, an interior dividing or partition plate; a, flanges for bolting or riveting the parts together; b, end passages or shelves, upon which the liquid flows from one side to 35 the other of the main casing; c, inclined passages or shelves, upon which the liquid flows in its passage through the apparatus from the top to the bottom; d, return-bends of the steam-pipe; e, sections of steam-pipe between the 40 return-bends; f, exhaust; g, steam-inlet pipe; h, side passages to the main air passage or tube.

45 The parts A B B' may be cast or made of suitable sheet or plate metal, and their size will depend somewhat upon the use for which they are designed. The form shown being designed for concentrating liquids, I make it about eight feet high and long, with a width of about three feet. These dimensions will give 50 a sufficient length of travel for the liquid. In

this construction, the exterior casings form the outer boundaries of the channel-ways, and the partition G forms the inner boundary, and as this is the main purpose of this partition or division plate, it is not important that it be continuous or entire, so long as sufficient remains to furnish complete or perfect channels in connection with the bottom G and the exterior casing; but as it forms the interior support for the channels, I prefer to make it continuous, as shown. 55 The steam-pipes d e are attached to or supported against the under side of the plates or bottoms of the channels b c, so that they do not come in contact with the liquid flowing through and down the channels, but act upon them by 60 heating the bottom of the channel, which is covered by the flowing material, and by a direct radiation of heat onto or in the liquid moving below them, and by this arrangement of the pipes in relation to the passing liquid it is impossible to scorch or burn the liquid or otherwise injure it by contact with the pipes, as the two do not in any case come in contact. The return-bends d of the pipes are not connected with the end shelves, b. The steam-pipes are attached irrespective of these shelves, so that the end sections, B B', can be placed in position after the pipes are properly attached to the section A. The shelves or channel-bottoms b are arranged in their respective end sections, so as 65 to meet the lower end of a shelf, c, on one side, and the upper end of a shelf, c, on the other side, and connect them together, so as to form continuous channels from the top to the bottom. The shelves or channel-bottoms b are 70 horizontal, as shown, and I prefer to make them this way, as they are more easily fitted to and connected with the shelves or channel-bottoms c. They may, however, be so formed as to connect with the bottoms c, so as to give 75 a uniform and continuous descent, and as such uniform descent is immaterial, I prefer to make them horizontal, and by making them horizontal I prevent the passing liquids from getting an accelerated movement in their passage downward. 80

I have shown only one steam-pipe under each shelf or channel-bottom; but it will be understood that a greater number may be used in the place of the one shown. When more 85

than one is used, they are connected at their upper ends by a coupling or cross pipe, and steam is admitted into them through such coupling.

- 5 For producing a circulation of steam through the pipes when more than one is used, and providing for the escape of the water of condensation, a cross-pipe may be connected with the exhaust-pipe and applied at the bottom.
- 10 Steam may be made to traverse the pipes in either direction, as the inlet and outlet pipes may be used in a reverse manner.

In putting the parts together, suitable packing material is to be placed between or under 15 the flanges *a*.

- For the purpose of exhausting the air from this device, I apply a passage, *C*, to one side or end of the casing, and, in order to give this passage a suitable capacity, I prefer to place 20 it on the outside, as shown; but it may be located inside. Each liquid-passage near the steam-pipe, or sufficiently above the channel-bottoms to prevent an overflow of the liquid, is provided with a passage, *h*, through which 25 the air is permitted to pass into the vertical passage *C*. This arrangement is for the purpose of working the apparatus under vacuum, and the exhaust-fan or other exhaust device is applied to the pipe or opening *D*.
- 30 In operation, the liquid to be concentrated or reduced in quantity passes in through the pipe or opening *E*, from which it passes to a shelf or channel-bottom, thence to the opposite side, and so on until the bottom is 35 reached, when it is discharged through the pipe *F*, which pipe is provided with a trap or is made long enough to furnish a sufficient check to the air to give the exhaust its proper operation, and the inlet *E* is also suitably 40 made for this purpose. This will be found a very efficient device for a vacuum-pan or for operation under an exhaust. It will also be found a very efficient device for operating in the reverse manner or under a blast, and the 45 only change required is to provide an air-opening at or near the bottom, and to close by a suitable register or otherwise the openings *h*; and if the apparatus is originally constructed for the purpose of applying the blast 50 only the openings *h* may be omitted in construction. In this latter form the blast will be applied at or near the bottom, and will pass out at the opening *D*, and carry with it

the vapors exhaled from the liquid over which it passes. The air in this method of 55 using the device may be wholly or partly heated outside; but it will be found, even with this arrangement, advantageous to use the interior pipes for heating the channels and the liquid, as with an exhaust or vacuum operation. 60

I do not claim, broadly, the use of a continuous descending channel, as that is shown and described in Patent No. 250,694, and one of the objects of this invention is to improve 65 the apparatus of said patent, and by this arrangement the desired number of these machines may be placed side by side, so as to occupy but little room space, while a greatly increased and enlarged evaporating capacity is 70 obtained in a comparatively small space.

The channels may be copper-lined, or the apparatus may be made of sheet-copper or plate-iron, and be partly copper-lined when made or when cast, to facilitate cleaning and to avoid 75 cementing or making the joint otherwise non-leaking.

What I claim as new, and desire to secure by Letters Patent, is—

1. The casing *A* *B* *B'*, in combination with 80 the channel-bottoms *b* *c* and the division-plate *G*, whereby the continuous channel is brought into a compact space and the channel is formed without risers or flanges attached to the channel-bottoms, substantially 85 as specified.

2. In an evaporating apparatus, the steam-pipes *d* *e*, located beneath the bottom of a channel and out of contact with the contents of the channel beneath, whereby the channels 90 and contents are heated without the contact of the steam pipes or passages with the liquid, substantially as described.

3. The combination of the vertical passage *C* with the casing *A*, having the side openings, 95 *h*, and the exhaust-passage *D*, substantially as specified.

4. The central section, *A*, having the steam-pipes attached to it, in combination with the removable end sections, whereby the device 100 may be opened without detaching the pipes, substantially as described.

NATHANIEL B. RICE.
